UNITED STATES PATENT OFFICE.

OTTO P. AMEND, OF NEW YORK, N. Y., ASSIGNOR TO HYDROCARBON CORPORATION, OF NEW YORK, N. Y.

APPARATUS FOR CRACKING OR CONVERTING OILS.

Application filed August 9, 1919. Serial No. 316,440.

To all whom it may concern:

Be it known that I, OTTO P. AMEND, a citizen of the United States, residing in the city of New York, borough of Manhattan, 5 county and State of New York, have invented a certain new and useful Apparatus for Cracking or Converting Oils, of which the following is a specification.

This invention relates broadly to the art 10 of cracking crude petroleum, heavy naphthas, kerosene, and higher-boiling hydrocarbon distillates or residuals, and converting the same into lower-boiling hydrocarbons, suitable for use in internal combustion engines, and for all other purposes for which 15 the low-boiling petroleum distillates are used. The process is applicable either to hydrocarbons of the paraffin or of the napthene or polymethylene series, or to mixtures of hydrocarbons of any series. The 20 process is preferably applicable to any of the higher-boiling petroleum distillates, such as kerosene, Mexican distillates, gas oils, and fuel oils.

25 The method long employed in the cracking of these hydrocarbon oils has been carried on in a metal still or tube under pressure exteriorly heated in any one of several ways, usually by means of a flame directed 30 thereagainst. The heat required to properly crack the oils is, however, relatively high, and, when externally applied, necessitates the raising of the temperature of the walls of the still to such degree, in order to properly crack the oil within, that their ability 35 to withstand the pressure within the still is seriously impaired and there is the great danger present of the walls giving away under the pressure and frequently occasioning the explosion of the still. For these reasons great care must be exercised in the carrying out of this process.

40 By the process of the present invention, however, I am able to secure any desired suitable vaporizing or cracking temperature 45 within the hydrocarbons, at the same time the sides and bottom of the still or digester are relatively cool, and the ability of the metal of the containing vessel to resist pressure is consequently not seriously impaired. 50 As a result, much higher pressures may safe-

ly be utilized than can be safely used by any process of external heating of oil in large stills. A pressure in excess of one hundred pounds may be safely used with large stills, 55 of say from 600 to 1,000 barrels capacity, with my process, whereas, such pressures are not practicable on a scale approaching this in any process in which the oil is heated by external heating. I secure this result by internal heating of the oil itself, by means of one or more high resistance heating elements, preferably of carbon, and preferably entirely immersed in the oil in the still or digester, and heated to the desired cracking 60 temperature.

65 One of the chief difficulties experienced in cracking and converting high boiling hydrocarbons into a low boiling distillate, by the use of heating elements submerged within 70 the oil and heated to incandescence, consists in the fact that when the element is of any size and is heated to the high heat required for successful cracking of the kerosene or other high boiling hydrocarbons, in the case 75 of kerosene, a heat of from a cherry red to a white heat being generally required, the heating element repels the oil and prevents intimate contact, and the oil at a distance from the heating element was merely vaporized without being cracked or converted into lighter hydrocarbon. The greater part of the condensate obtained is, therefore, non-converted oil. I have found, however, that 80 to overcome this repellent force of the heating elements, and to enforce contact or close proximity of the oil or oil vapors with such incandescent elements, pressure is required. The function of pressure in my process, while it incidentally raises the boiling point 85 and the temperature of the liquid, and although it is primarily to enforce close contact between the oil or oil vapors and the highly heated incandescent elements, it also largely arrests the gasification of the oil. 90 The amount of pressure required in any particular case to produce the best results, depends on the character of the oil treated, and on the temperature of the elements, and on the size of the receptacle. It is obvious 95 that the more pressure is applied to the oil to keep it in actual contact with the incan-

descent element, the more cracking and the less vaporization without conversion will take place, and that with an easily cracked oil pressures in excess of four atmospheres should preferably be used, say eighty pounds pressure. With a fuel oil, I prefer to use pressures of between eighty and one hundred and fifty pounds.

I have found that submerged resistance conductors made of carbon are most efficient, both because of the saturated character of the low boiling condensate obtained by their use, and because any carbon resulting from the cracking of the hydrocarbons, on being deposited on the heating elements does not effect them injuriously, whereas the formation of a hard carbon crust on metallic heaters due to the production of metallic carbides, causes a disintegration of the heating elements, rendering it unfit for practical use. The heating element employed may be in the form of rods, plates, sheets or tubes, or any other form.

By the use of internal heat electrically applied, I am able to regulate to a nicety the actual heating within the body of the oil. This more perfect regulation of the heat within the hydrocarbons enables a more constant quality of cracked product to be produced than is possible with external heating of the still.

The accompanying drawings illustrate an efficient type of apparatus, forming part of my invention, which may be employed in practicing the process herein described, although I desire to have it understood that other forms of apparatus may also be used.

Referring to the drawings, the figure 40 shows, more or less diagrammatically, partly in section, and partly in elevation, a substantially complete apparatus for practicing the process of this invention.

Referring to the drawings, A is a still having an oil inlet *a* and an inlet for introducing gas *b* extending nearly to the bottom of the still. The still is heated by means of a submerged carbon resistance element *c*, in the form of a plate or in tubular form as shown, the said element being provided with suitable terminals *d* and *e* properly insulated from the walls of the still.

55 Oil is introduced into the still through the pipe a which is fed either directly from a pipe a' , leading from any suitable source, or from a pipe a^2 through which the oil is forced by a pump a^3 , fed from any suitable source. In the pipe a^2 is included a series of preheated coils a^4 so that the oil, when fed in this manner, is partially heated before entering the still or retort A, for the purpose of minimizing the work required by the electrode c .

When current is passed through the electrode c , it is raised to a high degree of heat

and assumes a temperature anywhere from cherry red to a white heat degree, and pressure being maintained in the still as herein-after described, the cracking operation on the oil proceeds. The products of the cracking process rise in the still and enter a dome A' which is superimposed on the still, and passed off through an outlet B. The stack A' is preferably of such height and size that during the passage of the products of the cracking operation therethrough sufficient refluxing action will take place as to allow the return to the still of uncracked oil vapors carried along by the products of the cracking operation, and through such refluxing action raise the quality and quantity of the resulting product.

A further refluxing action may be carried on by inclining the draw-off pipe B in 85 an upward direction, although, if desired, the pipe B may extend in a horizontal direction if the tower A' is sufficiently high to properly carry out its functions.

The draw-off pipe B leads to a series of 90 cooling coils D which are housed by a casing E, through which a cooling medium, such as water, is circulated through inlet and outlet pipes e and e'. During the passage of products of the cracking operation 95 through these coils, the temperature is sufficiently lowered to condense the greater portion thereof, although a small percentage of such products remain in gaseous form. Leaving the coils D, the products of the 100 cracking operation pass through a pipe F into a receiving reservoir G. The liquid is trapped out in the reservoir G, but the gases flow off through pipe h leading to a tank H. The tank of the reservoir G has a draw-off pipe g through which the liquids may be 105 passed, drawn-off, and further treated if desired. A gage glass g' is preferably associated with the reservoir G so that one may determine the height of the liquid in said 110 reservoir, and the drawing off of such liquid is preferably controlled by valve g², included in the draw-off pipe g, and the valve g² is preferably normally closed.

In carrying out the process of this invention, pressure is maintained within the still during the cracking operation, and I preferably maintain this pressure through back pressure on the still from some portion of the system beyond the stack A'. To this end, pressure valves or regulators may be included in the system at various points. For example, a valve B' may be included in the pipe B as shown, which valve will maintain the pressure in the still, or, if desired, the valve B' may be omitted, and a valve F' included in the pipe F, though both of these valves may be omitted if the valve g^2 is maintained closed, and a valve H' included in the gas outlet pipe h. The valves B, F 130

and H' may be either automatic pressure release valves or valves of any well known type adjusted to hold back the pressure to the desired degree.

5 The pressure obtained in the retort is created by and is directly dependent upon the temperature of the heating elements and therefore upon the amount of electric current which is employed in the operation, 10 and is produced by the vaporization, dissociation and expansion of the hydrocarbons.

In the preferred method of practicing the invention, the gas in the tank H is preferably utilized for preheating purposes, and 15 to this end a pipe i leads to a burner I associated with the preheating coils a*, and in this pipe is included a valve i' by means of which the flow of gas may be regulated or cut off as desired.

20 The pipe b, hereinbefore referred to, is intended for the purpose of initially freeing the retort from air prior to the beginning of the process of cracking.

In commercially employing this invention, 25 the process may be continuous or intermittent as desired. That is to say, oil may be fed steadily to the retort A to take the place of the products of the cracking operation which are continuously passed off, 30 or said oil may be fed from time to time as desired.

In the drawings the heating element c is 35 shown as of tubular cylindrical cross section, but, in practice, it may well partake of other shapes, such for example, as the form of a plate. Many different shapes may be 40 employed with high efficiency and I therefore do not wish to be understood as limiting the shape of the heating element c to that shown. In any event, the heat from the heating element c will be imparted directly to the body of the oil in which it is 45 immersed, and the heating of such oil is not therefore dependent upon the heating of the retort in which it is contained. In practice, it is found that even when the oil is 50 subjected to the highest temperatures, the walls of the retort remain relatively cool, and the danger of exploding the retort, ever 55 present in the carrying out of externally heated retorts, is thereby entirely avoided. I am thus enabled to employ greater heat, as well as greater pressures, than could possibly be obtained in the externally heated retort, with practically no attendant danger.

Accordingly, the efficiency of the present 60 process is much higher than those of such processes as require external heating. As a result I am able to successfully crack kerosene, that is, a hydrocarbon having a range of boiling points above 130 degrees C. and below 260 degrees C. In neither of the well known Burton or Palmer processes can kerosene be commercially cracked, the Burton process serving only to operate upon paraf-

fins boiling above 260 degrees C., while the Palmer process is only applicable to paraffin residues boiling above 300 degrees C. The ability to successfully convert the kerosene into the highly volatile low boiling distillate by my process, and the inability of either the Palmer or Burton processes to successfully crack kerosene, brings out strongly the essential differences between the processes in question.

In instantaneous cracking and dissociation of the hydrocarbons induced by the contact with the incandescent carbon heating element produces a very rapid evolution of low boiling hydrocarbon vapors and rapid resulting increase of pressure. In order to obtain by my process a satisfactory conversion of kerosene into low boiling hydrocarbons, a small still should be used equipped with carbon conductors of relatively large 85 surface in proportion to the volume of oil, and the carbon resistance should preferably be heated to a bright red, or from a bright red to a white heat, although heats as low as a cherry red may be used with inferior 90 results. Where carbon resistances are used, heated to the above heats, there is comparatively little formation of tar and evolution of gas, the deposited carbon being porous and flaky and easily removable, and the 95 higher the temperature of the carbon heating element, the lighter in gravity is the condensate, and the freer it is from olefines and other unsaturated hydrocarbons, and from coloring matter.

In general, with all the hydrocarbons, the lower the boiling points, the higher is the dissociating temperature which should be used. Dissociation temperatures for gas oils and fuel oils of as low as about 500 degrees 105 C., and as high as a white heat of carbon, may be used, but with these high boiling oils I prefer to use temperatures from a cherry red to a bright red heat of carbon, or approximately from 750 degrees C. to 1500 degrees C. Pressures in excess of four and under ten atmospheres are sufficient, although higher pressure may be used.

In the foregoing description I have referred in different places to certain temperatures employed, time periods, etc., but I wish it understood that I do not limit myself to these specific features, nor to the specific details of construction of the apparatus employed. The invention should be construed 115 to cover equivalents, and is to be considered 120 as broadly novel as is commensurate with the appended claim.

Having thus fully described the invention, what I claim as new and desire to secure by 125 Letters Patent is:

An apparatus for cracking oil, comprising a still adapted to contain a relatively stationary body of the oil, an electric resistor having an extended heating surface arranged 130

- within the still and below the normal liquid level therein, a condenser and connections for conducting vapors from the still to the condenser, means arranged beyond the condenser for collecting gases uncondensed therein, means including a preheater for supplying oil to the still, and means for heating the preheater by combustion of gases including connections for supplying gases to the last named means from the gas collecting means.
